A. COOK AND C. GREENBAUM,
BRACKET FOR DISPLAY COUNTERS.
APPLICATION FILED DEC. 1, 1919.

1,378,400.

Patented May 17, 1921.

UNITED STATES PATENT OFFICE.

ARCHIBALD COOK, OF MOUNT VERNON, AND CHARLES GREENBAUM, OF NEW YORK, N. Y.

BRACKET FOR DISPLAY-COUNTERS.

1,378,400.

Specification of Letters Patent. Patented May 17, 1921.

Application filed December 1, 1919. Serial No. 341,622.

To all whom it may concern:

Be it known that we, ARCHIBALD COOK, a citizen of the United States, residing at Mount Vernon, in the county of Westchester 5 and State of New York, and CHARLES GREENBAUM, a citizen of the United States, residing at the city of New York, county of Bronx, and State of New York, have invented new and useful Improvements in a 10 Bracket for Display-Counters, of which the following is a specification.

This invention relates to counter display cases and the objects of our invention are to provide display cases the front top and sides 15 of which are of glass, the edges of which are protected by metal binding strips or a rail so that the edges of the glass will not be liable to be chipped when articles displayed in such cases are taken therefrom and handed 20 to customers or returned by customers and placed on top of the case or handed to the attendant. Also to provide a case which is composed of sections and to which sections may be added, or from which sections may 25 be taken away.

We attain these objects by the construction illustrated in the accompanying drawings in which—

Figure 1 is a plan view of a case consisting of two sections partly broken away.

Fig. 2 is an enlarged vertical section on the line 2—2 of Fig. 1.

Fig. 3 is a detailed section on the line 3—3 of Fig. 2.

Fig. 4 is a detailed section on the line 4—4 of Fig. 2.

Similar numerals refer to similar parts throughout the several views.

The brackets 1 are composed of members 40 2 and 3—3^e which are secured together by the rivets 4. The members 2 are provided at their upper ends with a ring 5 adapted to receive a guard rail 6 which is held in position by set screws 7. The members 2 are 45 provided with feet 2^a by which they may be secured to the counter upon which the display counter is supported. Between the members 3—3 is a web 8 of lesser width than the members 3—3^e which is secured in position by the rivets 4. Channels 9 are thus 50 provided to receive the ends of the plates of glass 9^a which form the front of the case. The members 3—3^e are brazed to the horizontal top member 3^b which is provided 55 with an upwardly turned lip 10. In the

base of the channels 9 is a pad 11 of rubber or other suitable material upon which the glass, which forms the front of the case, rests. The glass which forms the top of the case 14 rests on a pad 15 of felt or other 60 suitable material. In order to prevent injury to the rear edge of the glass forming the top of the case, we provide an angular strip of metal 16 which is secured to the upstanding lip 17 of the horizontal top member 3^b by screws 18.

In order to strengthen and stiffen the brackets inwardly curved braces 12 are brazed at one end to the inner upright members 3^e and at the other end to the horizontal 70 member 3^b and outwardly curved braces 13 are secured by rivets 29 to the braces 12 near their centers. The outwardly curved braces 13 are also secured to the horizontal member 3^b by rivets 30 and extend to the rear of 75 the horizontal member 3^b. They are also secured by rivets 31 to the inner upright members 3^e and are provided with feet 32, by which they may be secured to the support upon which the display counter is mounted. 80

We cover the joints between the plates of glass which form the top of our case with metal strips 19 secured in place by the bolts 20 which engage the metal clips 21. The ends of the case are bound by metal strips 85 22 which are secured to the brackets by screws 24.

The display case is firmly secured to the counter 26 by bolts 27 and nuts 28.

It is manifest that our cases may consist 90 of one or any desired number of units and that after a case has been completed units may be detached and removed or additional units added; that the structure is simple, light, strong and pleasing in appearance 95 and that the edges of the glass can not be readily chipped or broken by striking them with plates, dishes or other articles which are displayed therein which renders them especially suitable for use in restaurants, delicatessen stores and the like. 100

The rail or bar 6 not only fully protects the edge of the glass 14 but is ornamental in effect.

Having described our invention we claim: 105

1. A bracket for display counters comprising in combination upright members, a horizontal member, an inwardly curved brace secured at one end to one of said upright members and at the other end to said 110

horizontal member, an outwardly curved brace secured at its lower end to said upright member, at its upper end to said horizontal member and centrally to said inwardly curved brace and having feet by which the bracket may be secured to its support, a support secured to said upright members having a ring at its upper end to receive a guard rail and a foot by which it 5 may be secured to the support upon which the display counter is to be mounted.

2. A bracket for display counters comprising in combination a horizontal member adapted to support a glass plate which forms 10 the top of the counter, spaced upright members brazed at their upper ends to said horizontal member, a web of lesser width than said upright members secured between said upright members so as to provide channels 15 for receiving and holding the glass plates 20

which form the front of the counter, an inwardly curved brace secured at one end to said horizontal member and at the other end to the inner of said upright members, an outwardly curved brace secured to the inner 25 of said upright members near the lower end thereof and at the other end to said horizontal member and to said first mentioned brace near the center thereof, said outwardly curved brace being also provided with a 30 foot which may be secured to the support upon which the display counter is to be mounted, a guard rail and a support secured to said upright members having a ring at its upper end adapted to receive the guard 35 rail and a foot by which it may be secured to the support upon which the display counter is to be mounted.

ARCHIBALD COOK.

CHARLES GREENBAUM.
